UNITED STATES PATENT OFFICE.

PIETER DE LANGE AND ROBERT AERNOUT BARON VAN LYNDEN, OF UTRECHT, NETHERLANDS, ASSIGNORS TO NAAMLOZE VENNOOTSCHAP DE NEDERLANDSCHE THERMO-TELEFOON MAATSCHAPPIJ, OF UTRECHT, NETHERLANDS, A CORPORATION OF NETHERLANDS.

THERMIC TELEPHONE.

1,290,114.

Specification of Letters Patent.

Patented Jan. 7, 1919.

Application filed November 4, 1915. Serial No. 59,622.

To all whom it may concern:

Be it known that we, PIETER DE LANGE and ROBERT AERNOUT BARON VAN LYNDEN, both subjects of the Queen of the Netherlands, and residing at Utrecht, in the Netherlands, have invented a new and useful 5 Thermic Telephone, of which the following is a specification.

This invention relates to thermic telephones its object being to regulate the intensity of the sound reproduction by varying the volume of the sounding chamber. With this object in view, we so construct the sounding chamber that the parts 15 inclosing it may be displaced relatively to each other. We may also provide means for regulating the area of the sound openings in said sounding chamber.

Reference is to be had to the accompanying drawings in which our invention is 20 illustrated by way of example.

Figure 1 represents an enlarged sectional elevation of a thermic telephone according to our invention and adapted to be directly 25 introduced into the auditory passage of the human ear, Fig. 2 is a plan view of Fig. 1, Fig. 3 illustrates in elevation, partly in section, a modified construction, provided with a separate receiver adapted to be introduced into the ear, Fig. 4 is a cross-section on line A—B in Fig. 3, and Fig. 5 is a central longitudinal section of a further modification.

Referring to Figs. 1 and 2 the heating 35 conductors 1, which may be of any suitable construction and electrically connected in any suitable manner are mounted on a support 2 held in position within a tubular casing 3 by means of a plug 4 screwed into 40 one end of the casing. Through an opening in the bottom of the plug 4 the current conductors 5 and 6 are passed. The tubular casing 3 is closed at the top by a cover 8 held in position by a pressed-in ring 9 45 and provided with a plurality of apertures 7. A sleeve 10 is adapted to slide on said casing. The lower rim of sleeve 10 has a collar 11 in which is a packing ring 12. The cover 13 of sleeve 10 has apertures 14 50 corresponding in position to the apertures 7 of cover 8.

By pulling out the sleeve 10 in the manner of a telescope the volume of the sounding

chamber may be increased or reduced as desired, an additional sounding chamber 16 55 being formed, as indicated in dot and dash lines in Fig. 1 which additional chamber is connected to chamber 15 by the apertures 7.

When the sleeve 10 is turned on the 60 casing 3, the apertures 7 and 14 will no longer register perfectly. This affords a means of varying their effective area as desired. It will be understood that, with the construction shown, this is only possible 65 when the cover of sleeve 10 rests on the cover 8, but the apparatus might easily be modified so that the covers 13 and 8 remain engaged for any position of sleeve 10. This may be done, for instance, as shown in Fig. 70 5 where the sleeve 10 slides on the casing 3 as in Fig. 1, but the upper end of the casing opens directly into the sleeve, and the latter has a small plate 8' pivoted to it, the apertures 7' of this plate registering 75 more or less with the apertures of the sleeve head 13 as the plate is turned, which may be effected by means of the projecting pivot pin.

With the described improved construction, 80 by which the volume of the sound chamber as well as the area of the passages for the sound waves can be regulated, the sound effect of the thermic telephone can readily be adapted to any requirements within wide 85 limits.

A somewhat modified construction is shown in Figs. 3 and 4, in which the tubular casing 20 contains a plurality of superimposed groups of heating conductors 90 17 mounted on supports 18 which are secured in place within the casing 20 by a screw plug 30 similarly as described with reference to Fig. 1. On the casing 20 a 95 slidable sleeve 21 is guided. At its upper end, the casing 20 carries a resilient spider 22 the ends of which pass through slots 24 in the casing 20 and form abutments for a shoulder 25 at the end of casing 21. In 100 this manner, the spider 22 limits the upward movement of the sleeve 21. The upper part of sleeve 21 is of cap-like form and has a connecting nipple 26 to which is attached a flexible tube 27 terminating in a receiver 28. The latter is adapted to be 105 introduced into the auditory passage of the

human ear. By sliding the sleeve 21 on the casing 20, the volume of the sounding chamber may be increased and reduced, as desired.

5 The particular arrangement and connection of the heating conductors, as well as the method of securing them to their support, have no bearing on our present invention.

We claim:

10 1. In a thermic telephone, a casing, heating conductors within said casing, a sounding chamber, and means for varying the volume of said sounding chamber.

15 2. In a thermic telephone, a casing, heating conductors within said casing, a sounding chamber, and means adapted to slide on said casing for varying the volume of said sounding chamber.

20 3. In a thermic telephone, a casing, heating conductors within said casing, a sounding chamber and a sleeve adapted to slide on said casing.

25 4. In a thermic telephone, a casing, heating conductors within said casing, a sounding chamber, means for varying the volume of said sounding chamber, apertures for the passage of the sound waves, and means for varying the area of said apertures.

30 5. In a thermic telephone, the combination of a casing containing a sounding chamber and heating conductors coöperating with said sounding chamber, with a sleeve slidably mounted on the casing and having a perforated top for the passage of the sound

35 waves.

6. In a thermic telephone, the combination of a casing containing a sounding chamber and heating conductors coöperating with said sounding chamber, with a sleeve having a perforated top for the passage of the sound waves, said sleeve being mounted on the casing and adapted to slide thereon longitudinally and thereby to increase the volume of the sounding chamber,

and means for limiting the sliding movement of said sleeve. 45

7. In a thermic telephone, the combination of a casing containing a sounding chamber and heating conductors coöperating with said sounding chamber, with a sleeve 50 having apertures at the top for the passage of the sound waves, said sleeve being mounted on the casing and adapted to slide longitudinally thereon, and thereby to increase the volume of the sounding chamber, means 55 for guiding said sleeve on said casing, said means being adapted to form a tight joint between said casing and said sleeve, and means for limiting the sliding movement of said sleeve. 60

8. In a thermic telephone, the combination of a casing having a perforated top and containing a sounding chamber and heating conductors, with a sleeve adapted to slide and to turn on said casing and having a 65 perforated top, the perforations of which are adapted to register with the perforations in the top of said casing.

9. A thermic telephone, comprising in combination, heating conductors, a support 70 for same, a casing within which said heating conductor support is mounted in such a position that a sounding chamber is formed in front of the heating conductors, a screw plug for holding said support in position 75 within said casing, means for connecting the heating conductors to the current conductors, a perforated top plate on said casing, a sleeve adapted to slide and to turn on said casing, a top plate on said sleeve, adapted 80 to rest on the top plate of said casing and having perforations arranged to register with the perforations in the top plate of said casing. 85

In testimony whereof, we have signed this specification.

PIETER DE LANGE.
ROBERT AERNOUT BARON VAN LYNDEN.
